DESIGN FOR A GAME BOARD

Werner F. Otte, New York, N. Y.

Application December 13, 1940, Serial No. 97,291

Term of patent 7 years

To all whom it may concern:

Be it known that I, Werner F. Otte, a citizen of the United States, residing in New York city, in the county of Bronx and State of New York, have invented a new, original, and ornamental Design for a Game Board, of which the following is a specification, reference being had to the accompanying drawing, forming a part thereof.

In the drawing:

The drawing is lined for contrasting color.

I claim:

The ornamental design for a game board, as shown and described.

WERNER F. OTTE,
